CANDLE AND METHOD RELATING THERETO **REISSUED**

Application filed November 10, 1930. Serial No. 494,459.

This invention relates to lighting devices, and particularly to a sacramental light. Specifically, the invention contemplates a new and improved sanctuary light.

5 An object is to provide a lighting device which will be more effective in its operation than the previously known lighting devices of its general type.

Another object is to provide a sacramental 10 light which will burn for a long time, and clearly indicate, all during such time, that it is burning.

Another object is to provide an improved 15 candle for use as part of a sanctuary light, and which may be used without requiring modification of the present-day fixtures, such, for example, as the usual ruby glass, the conventional base therefor, and other ancillary parts.

20 A further object is to provide an improved means for preventing the formation of a deep "well" in the top of the fuel body of a candle of relatively large average diameter, during the critical period shortly after the 25 candle is lighted.

Still another object is to provide a candle which will be better adapted for packing and shipping than are candles of the class herein shown, heretofore used.

30 Another specific object is to provide a sacramental candle, for use say in common types of sanctuary light equipment, etc., which candle will not deposit soot or wax on the inside of the usual glass globe or on the candle supporting base.

Other objects and novel features of the invention will become apparent from the following description, which relates to the accompanying drawings. The drawings show the preferred forms of the apparatus, and the characteristic features of the method. The essential novelty is defined by the claims.

In the drawings, Fig. 1 is a central sectional view, showing a known type of sanctuary light globe, a conventional base and insect guard therefor, my improved candle being shown in place within the globe; Fig. 2 is a fragmentary sectional view of the upper portion of the candle, and showing, particularly, a device for protecting the candle

when used in low temperatures; Fig. 3 is a sectional view of the improved candle, showing, in diagram, the manner in which the candle operates, and showing, further, a preferred construction for preventing the wick 55 from tipping over when nearly consumed; Fig. 4 is a diagrammatic view, illustrating the condition of the fuel and flame when the candle is, say about half consumed; Fig. 5 is a sectional view of the base portion of the 60 candle, (nearly consumed), the view being taken substantially along the lines 5—5 on Fig. 3; Fig. 6 shows a modified wick support; Fig. 7 shows a modified form of candle, the upper portion thereof being broken 65 away in central cross-section; Figs. 8 and 9 are still other modified forms of the invention, in operation; and Fig. 10 shows the preferred manner of packing the candle for shipment.

The present invention is an improvement 70 in illuminating devices of the class including sanctuary lights. The lights of this class heretofore used employed solid fuel and a wick, the fuel being in suitable, say elongated, 75 body form and adapted to burn in a hollow globe, either spaced from the inner surfaces thereof horizontally ("ruby cylinder" type), or set into globes which were in the nature of cups or containers intimately embracing the 80 fuel material horizontally on all sides, (as though poured into and solidified therein). The latter arrangement of globes ("lily" type) have always been characterized by having wide mouths, and sloping sides, usually 85 if not always permitting the solidified material to be inserted into and withdrawn therefrom. The "ruby cylinder" type often requires a follower or burner to assist in preventing dripping and the formation of deep 90 wells in the fuel body, and such ancillary equipment is not satisfactory, principally due to the tendencies thereof, viz: to become cocked on the fuel body, wedged against the 95 ruby cylinder, to drown the flame by submerging the wick upon too rapid travel downwardly, etc. The above and other disadvantages of followers, and, moreover, the need for follower devices of some sort with this type of light, are generally recognized. 100

- The other ("lily") type of sanctuary light does not permit the use of a follower, but this has disadvantages of its own and some in common with the ruby cylinder type—particularly the nuisance of having to laboriously clean out wick and wax deposits and soot. The principal disadvantage of the "lily" type, however, is the formation of a deep well in the fuel body around the wick when this type of light is started burning in low temperatures or where the temperature suddenly lowers at any time during the burning. If a deep well forms, then the light appears to have gone out though it may still be burning and after a well is formed and the temperature suddenly rises, then the sides of the well collapse or slide down, causing the melted fuel at the center to rise and extinguish the flame.
- All the disadvantages incident to using the prior devices above mentioned are overcome by the new arrangement hereinafter described.
- In Fig. 1 the ruby glass is shown at A, resting at its bottom margin, in a rim *g* of a suitable base G. The bell-mouthed upper end B of the ruby glass is adapted to support a suitable reticulated insect guard indicated diagrammatically at H. The base G has below the shouldered rim *g* an annular shoulder *g'* adapted to support the usual form of candle, and which shoulder I may also make use of to support the improved candle.
- As shown in Figs. 1 to 10, the candle comprises a single piece glass vessel 1, having a restricted mouth at 2, at the top. The candle has a wick 3, preferably centrally thereof and running the entire length of the vessel. The preferred wick is the conventional metal cored wick, that is to say, one in which there is incorporated a strand of soft metal, such as lead, which metal melts as the wick burns down, but remains solid enough at and below the charred portion, to prevent the free end of the wick from bending over into the melted wax.
- The fuel supplying body 4 may be ordinary candle wax, any wax of low melting point obtainable on the market, as such, being suitable. The wax, which is melted and poured into the top of the vessel may fully or partially fill the vessel, preferably partially, about as shown in Fig. 1.
- To support the wick, when the fuel is about consumed, I preferably employ a suitable block of inexpensive material, such as wood, (see Fig. 3 at 5), the block being apertured as at 6, to receive the lower end of the wick.
- To protect the wood from burning, as well as to weigh down the block against floating in the melted wax and allowing the wick to tip over, there is shown a small plate of sheet metal 7, apertured as at 8, to receive the wick. In order that this plate may function

to substantially center the wick, with relation to the vessel, the plate may have one of its dimensions, say its length, corresponding nearly to the inside diameter of the vessel at the bottom thereof while the width of the plate (see Fig. 5) is preferably substantially the same as the block. This wick supporting arrangement may be considerably modified. For example, as shown in Fig. 6, the wooden block 9 may be covered on its top side with a suitable coating of non-inflammable material, for example, with water-glass, as at 10, and the block may be weighted, as by a small lead insert 12, in which case the weight of the wick supporting device is depended upon to hold the lower end of the wick centrally of the vessel.

In moulding, the preferred method is to place a "dummy" wick, (preferably a steel wire) in the vessel in the desired location for the wick. The wire is of course thrust through the plate 7 and into the block 5, thus locating these members. The melted wax is then poured into the vessel. After the wax has hardened, the wire is withdrawn, and the wick then fully inserted into the space left by the wire. The wick is of course previously treated to render it stiff, as by drawing the same through paraffin.

Referring again to the top of the vessel, it will be seen that this converges gradually as at 15, to the restricted mouth 2, the smallest diameter of the mouth, as shown, being slightly below the top edge of the vessel. This relationship of the smallest diameter to the top edge is not essential, but, in manufacturing the vessel, it is found desirable to provide some sort of strengthening bead effect, as at 16; and because of this, and in order to maintain a uniform thickness of glass, the resulting vessel is somewhat widened at the mouth, as at 17.

Various stages in the course of burning the candle are shown in Figs. 2 to 5. In Fig. 2 the fuel has been consumed to a point slightly below the most restricted portion, 2, of the vessel mouth, and at this point, under ordinary conditions, it will be found that a pool 20 of melted wax lies over the entire upper face of the solid wax, the depth of the pool varying in the neighborhood of $\frac{3}{16}$ " in a vessel of the proportions shown, and having a mouth diameter, (at 2) of about $1\frac{3}{8}$ ". The proximity of the glass neck of the vessel to the flame conducts enough heat to the adjacent portions of the fuel to melt the same at the top clear across and thus prevent the formation of any well at this, the most critical period in the burning operation. Now, as the candle burns down, this pool of melted wax remains of substantially uniform depth, (with the surrounding temperature substantially constant), clear to the wall of the vessel. The depth of melted wax varies according to room temperatures, but,

the depth, notwithstanding radical changes in temperature, is never such as to extinguish the flame by drowning the wick. Fig. 3 illustrates substantially the condition which exists when the pool of melted wax reaches the cylindrical portion of the vessel, and Figs. 4 and 5 illustrate the conditions existing when the candle is about half and nearly entirely consumed, respectively.

10 It may seem surprising that the candle continues to burn below the neck of the vessel, as in Figs. 3 and 4, but apparently sufficient oxygen in fresh air is drawn down into the vessel about its outer walls (see arrows α) by reason of the rapidly rising column of hot burned gases (see arrows γ). Of course, this rising column of burned gas diffuses in the downwardly directed column of fresh air. Nevertheless, it is obvious that the 20 colder, fresh air will continue to move down, and the warm, exhausted air, upwardly, thus continually feeding the flame with oxygen.

It may now be seen, with reference to the diagrammatic illustration of air currents in 25 Figs. 3 and 4, that sufficient heat is imparted to the glass walls of the vessel, both by diffusion of the hot exhaust gases and heat radiation, to insure that the wax will entirely melt off the walls, and not accumulate on 30 the vessel walls, to such an extent as to obstruct the light.

When the fuel is nearly consumed, as shown in Fig. 5, the weight of the metal plate 7 prevents the block 5 from tipping over (as by floating in the melted wax) and at the same time the plate prevents the block from burning. In the arrangement illustrated, substantially all the wax at 20' will be drawn up over the edge of the plate 40 7, to the wick, leaving only a slight residue at the bottom of the vessel, when the flame finally goes out.

A feature of the invention is illustrated in Fig. 2, wherein I have shown means for use 45 in cold weather, to provide a dead air space between the upper end of the vessel 1 and the ruby glass. This may comprise simply an annular disc of fibrous material, such as heavy cardboard or asbestos 25, having an 50 opening at 26 to telescope the outer rim of the vessel, at 16, and to be supported at its outer edge by the bell-mouth of the ruby glass. Any suitable means, such as loops 30, may be fastened to the disc 25, to permit the 55 disc to be easily removed, when desired. These devices 30 may comprise metal inserts such as shown, metal or paper tabs riveted to the disc; or, in fact, ordinary string loops 60 will serve. In warmer weather it is highly 65 desirable that air shall circulate freely in the space between the vessel 1 and the ruby glass, to keep the walls of the vessel comparatively cool, hence the disc 25 is used or omitted, depending on expected temperatures. In extremely cold weather, the can-

dle furnishes plenty of heat to insure that all the wax will be melted away from the inner vessel walls.

Referring now to Fig. 7, this merely illustrates that the vessel does not have to be 70 made in one piece, there being a lower member 35 and a separate, upper neck member 36 arranged, for example, to fit into an annular shoulder 37, on the member 35.

While it is essentially desirable that the 75 walls of the vessel 1 shall be translucent to such an extent as to allow the flame to be seen through the wall of the vessel, and thence through the ruby glass, it is not entirely essential that all of the vessel 1 shall 80 be translucent. For example, in Fig. 8 the restricted mouth of the vessel may be afforded by an annular opaque hood such as illustrated at 40. This, as shown, has an upwardly converging portion 41, (shown conical), 85 a flange at 42 to abut the top of the glass vessel member 43, and a depending skirt 44 to form a tight fitting joint with the upper end of the vessel 43. This device has a disadvantage not present in the previously described arrangement, namely, that part of the flame cannot be seen directly when it reaches the point illustrated in Fig. 9. Moreover the metal cap is not nearly so effective in preventing "welling" of the wax in 90 very cold weather principally because it is difficult to obtain a close enough fit between the metal and the glass to insure that adequate heat will be conducted to the side walls. Further the wax cannot readily be moulded 100 in the restricted portion of the device to reduce the diameter of the fuel body at the top as in the case of the one piece casing according to Fig. 1 for example. However, portions of the flame will stand either above or 105 below the member 40 at all times, sufficiently to light up the ruby glass and clearly indicate to the observer that the lamp is burning.

Referring to Fig. 10, it will be seen that 110 the method of packing the improved candle, particularly the form shown in Fig. 1, may simply consist in nesting a plurality of the vessels, complete with wicks and fuel bodies, in an ordinary packing container 50, there being suitable fibrous partition members 51 115 interposed between the vessels to prevent breakage. The advantage of this method of handling the candles will be clearly appreciated when it is considered that, ordinarily, candles must be packed with a great 120 deal of care and in adequate stiffeners, to prevent breakage and distortion.

I claim:

1. A solid fuel candle uniformly and intimately embraced by a glass bottle, and held 125 in the bottle by the restricted mouth thereof.
2. A candle comprising a fusible fuel body, a wick contained thereby, and a relatively non-fusible translucent container of fixed length having a restricted mouth, the con- 130

tainer, including the restricted portion thereof, substantially uniformly and intimately embracing said fuel body.

3. As a new article of manufacture, a relatively non-fusible translucent rigid casing of fixed length, means providing a restricted mouth for the casing, and fusible solid fuel candle material contained in the casing in substantially uniform intimate contact with the side walls thereof and perforated to receive a suitable wick.

4. A candle, comprising a relatively non-fusible translucent elongated casing closed at the bottom and having an opening at the top, fusible solid fuel candle material contained therein in intimate uniform contact with the walls thereof, and means separate from said casing and fitting the same at the upper end thereof, restricting the opening.

20 5. A candle, comprising a translucent casing formed in one piece, closed at one end and having a restricted mouth at the other, and a fusible solid fuel body within the casing, of greater diameter than the restricted 25 opening and adapted to be consumed in place by a suitable wick.

6. A candle, comprising a solid fusible fuel body and a suitable wick, there being a relatively deep translucent vessel embracing the body in substantially uniform intimate contact therewith throughout the vertical height of said body, and there being heat conducting means associated therewith in overhanging relation to the fuel body and 35 joining said vessel for conducting the heat generated at the candle flame to the vessel wall to thereby maintain the vessel walls free from unmelted fuel.

7. In combination with a candle having an 40 elongated fusible solid fuel body, a rigid translucent casing of fixed length enclosing said body for substantially the full length thereof and in such proximity to said body that the walls of the casing will retain the 45 pool of melted fuel material as the candle burns, and heat conducting means associated with the top of the casing and extending inwardly in overhanging relation to said body to conduit the heat of the flame to the casing walls and thereby prevent congealing of fuel material on the casing walls opposite the flame.

8. A sanctuary light comprising an outer protective translucent hollow body, a candle 55 contained thereby and incorporating a fuel supplying body in a translucent rigid casing, and annular removable means interposed between the upper end of said casing and the adjacent wall of said hollow body to form a 60 dead pocket below said means.

9. A candle, comprising a relatively non-fusible translucent container of fixed length, an elongated fusible fuel body adapted to be consumed by a suitable wick, said body being disposed in fixed upright position in the

container, the side walls of the container being brought inwardly to form a restriction embracing the upper portion of the fuel body, the restricted portion of the container intimately and uniformly embracing the side surfaces of such upper portion of the fuel body, whereby when the candle is lighted and the upper portion of the fuel is being consumed, the restricted portion of the container will first confine the melted fuel in a relatively small pool and will thereafter overhang the top surfaces of the remaining solid fuel body in the manner described to retain the heat generated by the candle flame.

In testimony whereof, I hereunto affix my signature.

HUBER H. ROOT.
